To all whom it may concern:

Be it known that I, Ferdinand W. In the drawing:

Figure 1 is a front view of a combined bottle and cap closure showing my new design;

The characteristic features of the design reside in the combination of a body having concave sides, a flat front with a rectangular panel, a flat rear, convex shoulders, and a substantially cylindrical cap, whose walls are decorated by a series of vertical grooves, reaching almost to the shoulders.

I claim:

The ornamental design for a combined bottle and cap closure substantially as shown and described.
